UNITED STATES PATENT OFFICE.

BENJAMIN GILOWITZ, OF NEW YORK, N. Y., ASSIGNOR OF ONE-HALF TO HARRY ARONSTAM, OF BRONX, NEW YORK, N. Y.

SHOE-TREAD-FORMING SHEET AND MOLD THEREFOR.

Application filed October 22, 1925. Serial No. 64,257.

My invention relates to the manufacture of treads for shoes, from rubber or any desired composition, and it is to be understood that by the term "shoe treads", I mean sole members or heel members, including complete heels as well as lifts.

One object of the invention is to provide a relatively thin flexible sheet having integral thickened portions shaped to form 10 shoe treads when cut from said sheet.

Another object is to provide the sheet and the shoe treads thereof, with a concavo-convex form, so that the treads, when cut from the sheet and applied to shoes will 15 snugly engage the latter.

A still further object, in the production of a sheet embodying body sole members and heel members, is to locate said heel members between the sole members, so as to economize in space and utilize portions of the 20 sheet which could not otherwise be used to advantage.

Yet another object of the invention is to provide a new and improved form of mold 25 for the production of a sheet such as that above discussed.

With the foregoing in view, the invention resides in the novel subject matter herein-after described and claimed, the description 30 being supplemented by the accompanying drawings.

Figure 1 is a top plan view of a mold with the upper section removed, disclosing a molded sheet in readiness for removal from 35 the mold.

Figure 2 is a vertical transverse section as indicated by line 2-2 of Fig. 1.

Figures 3 and 4 are longitudinal sectional views as indicated by lines 3-3 and 4-4 40 of Fig. 2.

Figure 5 is a plan view of one form of sole which may be formed in the mold.

Figures 6 and 7 are detail sectional views as indicated by lines 6-6 and 7-7 of Fig. 5.

Figure 8 is a view similar to Fig. 1 showing a different form of construction.

Figures 9 and 10 are respectively a trans-verse and a longitudinal section as indicated by lines 9-9 and 10-10 of Fig. 8.

Figure 11 is an elevation of a pair of the soles formed by the mold disclosed in Figs. 8, 9 and 10.

Figure 12 is a view similar to Figs. 1 and 8 but disclosing a mold for producing only heel members such as complete heels or lifts.

Figure 13 is a longitudinal sectional view on line 13-13 of Fig. 12.

Figure 14 is a plan view of a heel formed by the mold shown in Figs. 12 and 13.

Figures 15 and 16 are detail sectional views on lines 15-15 and 16-16 of Fig. 14.

The form of construction disclosed in Figs. 1 to 4 will first be described. The mold shown in these figures, comprises a core C and an outer mold member O, the latter 65 being preferably formed of separate sections connected detachably with each other by dowel pins or the like 17. The core C is shown of cylindrical form and the outer mold member O is correspondingly shaped, 70 but it is to be understood that these members may be of any desired cross sectional shape, for instance semi-circular.

In addition to the transverse convexity imparted to the molding surface 18 of the 75 core C, the two end portions of this core member are preferably longitudinally convex as disclosed in Figs. 3 and 4. Similarly, the molding surface 19 of the outer member O, is transversely concave due to its circular form, and is longitudinally concave at both of its end portions. Suitable means are provided to space the molding surfaces 18 and 19 a slight distance apart, so as to form a thin concavo-convex sheet 20 be- 80 tween them. In the preferred construction, this spacing means is in the form of a ridge 21, one of these ridges being disposed at each end of and integral with the core mem- 85 ber C.

At least one of the mold members O-C, preferably the member O, is formed with a plurality of recesses to permit the formation of shoe treads integrally with the sheet 20. In the present disclosure, some of these recesses are indicated at 22 and are shaped to form sole members S upon the sheet 20, while other recesses 23 are shown, shaped to provide heel members which are preferably rather thin to constitute lifts L. If desired, 100 all of the recesses 22 and 23 may be of uniform depth, or they may be of any desired, different depths.

The inner side which may well be termed the bottom of each of the recesses 22 and 23, 105 is curved in conformity to the opposed molding surface with which it co-operates in forming the sole or heel member. This is seen most clearly in Figs. 2 and 4, special attention being directed to the recesses 22 110

shown in these views. Referring to Fig. 2, it will be seen that since the inner side or bottom of the recess 22 co-acts with the opposed surface 18 of the core C, the latter being convex, said inner side or bottom is concave. Similarly, referring to Fig. 4, it is to be observed that as the inner side or bottom of the recess 22 co-operates with the surface 18 which is longitudinally convex, said inner side or bottom is longitudinally concave to the same extent. By this formation, all of the shoe treads S and L produced by the mold, will possess both transverse and longitudinal curvature, so that the upper side 15 of each tread is concave and its lower side convex, which greatly facilitates tight securing of the tread to the shoe.

The recesses 22 are so related and the ridges 21 so shaped, that the latter form the rear ends of the sole members S, on oblique lines, as fully shown in Fig. 1, and it will be observed that the recesses 23 are so located as to form the lifts or the like L upon the sheet 20, in spaces between the sole members, thus utilizing these spaces which could not otherwise be advantageously used.

Either one of the mold sections O—C may be provided at any desired points with pins P to hold washers W to be embedded in the sole or heel members, and it will be understood that these washers may be of the usual or any desired form or forms. In the formation of the sheet, I also prefer to make provision whereby a fabric strip F will be disposed across the rear end of the sole, as disclosed in Figs. 5 and 6. Preferably, the washers for the soles are located about as shown in Fig. 5 and it may be explained that in most instances, I prefer to provide each lift or heel member with only one washer at its center.

After the plastic material from which the sheet and the shoe treads are to be formed, is appropriately engaged with the mold and the sections of the latter are tightly clamped together, the material is heat treated and during such treatment, it runs into all of the recesses 22 and 23 and is eventually cured, so that when the outer section of the mold is removed, the thin sheet 20 with the integral treads S and L, may be removed. When this sheet is of continuous form, as in the present disclosure, it must of course be longitudinally cut on one or more lines, before it can be disengaged from the core C. In the condition taken from the mold, the sheet is in readiness to be supplied to shoe repair-men and the like and whenever soles, lifts or the like of one size or another are needed, they are simply severed from the main body of the sheet 20, and may be quickly and easily attached.

The general construction disclosed in Figs. 8, 9 and 10 is substantially the same as that above described and hence only the

variations in construction will be specifically referred to. This mold is of a construction to form soles S' and complete heels H', the heel-forming recesses 23' of the outer mold member being considerably deeper than the sole-forming recesses 22'. The inner extremities of the ridges 21' are also differently shaped from the ridges 21, and the recesses 22' are so positioned that said ridges properly form the rear ends of the soles S'. 75

Like the mold first described, the device shown in Figs. 8, 9 and 10 may be of cylindrical form in transverse section, or of any other desired shape. Figs. 12 and 13 disclose a mold which in all substantial respects is 80 about the same as those previously described. This mold, however, is intended for the formation of only a plurality of heel members H', either heel lifts or complete heels, the molding recesses for these heel members being indicated at 23'. Obviously, this form of mold, like the others, may be of any desired cross sectional shape.

As excellent results are obtainable from the general construction illustrated, such 90 construction is preferably followed. However, within the scope of the invention as claimed, modifications may of course be made.

I claim:

1. A mold comprising two complementary members having opposed molding surfaces and means for spacing them a slight distance apart to permit the formation of a thin sheet between them, at least one of said 100 mold members having a plurality of shoe tread molding recesses to provide the molded sheet with integral shoe treads certain of said tread molding recesses being so arranged with respect to said spacing means 105 and said spacing means so shaped that the latter will form the rear ends of said recesses and the treads molded therein on oblique lines.

2. A structure as specified in claim 1; 110 certain of said recesses being shaped to form sole members, others of said recesses being shaped for the formation of heel members and being disposed to locate such heel members upon portions of the sheet between the 115 sole members.

3. A mold comprising two complementary members having opposed molding surfaces, ridges formed at each end of one of said members whereby said molding surfaces are 120 spaced a slight distance apart, the inner edges of said ridges being in the form of a series of curves, one of said mold members having a plurality of shoe tread molding recesses, certain of said recesses being so arranged with respect to said spacing ridges 125 that the curved inner edges of the latter will form the rear ends of said recesses and the treads molded therein on oblique curved lines.

4. A mold comprising an inner member and an outer member having both longitudinal and transverse concave and convex molding surfaces respectively, and means shaped for the formation of heel members and being disposed to locate such heel members upon portions of the sheet between the sole members. 25
- 5 for spacing said surfaces a slight distance apart to permit the molding of a thin concavo-convex sheet between them, at least one of said members having shoe-tread molding recesses opening through its molding surface 30
- 10 to provide the molded sheet with a plurality of integral thickened shoe treads, the inner sides of said recesses acting to form one side of the treads and being substantially concentric with the opposed molding surface 35
- 15 which forms the other side of said treads, whereby the treads are each provided with both a longitudinally and transversely concaved side and both a longitudinally and transversely convexed side. 40
- 20 5. A structure as specified in claim 3; certain of said recesses being shaped to form sole members, other of said recesses being

6. An article of manufacture comprising a relatively thin flexible sheet of concavo-convex form both longitudinally and transversely and embodying comparatively thick integral portions protruding from at least one of its sides and shaped to provide shoe treads when cut from the sheet said treads being of concavo-convex form both longitudinally and transversely. 35

7. A structure as specified in claim 6; certain of said protruding portions being sole members, other of said protruding portions being heel members, the latter being disposed between the sole members. 40

In testimony whereof I have hereunto affixed my signature.

BENJAMIN GILOWITZ.
